DESIGN FOR A CHAIR

Harold F. Scribner, Westfield, N. J.

Application March 12, 1937, Serial No. 68,133

Term of patent 7 years

To all whom it may concern:

Be it known that I, Harold F. Scribner, a citizen of the United States, residing at Westfield, in the county of Union and State of New Jersey, have invented a new, original, and ornamental Design for a Chair, of which the following is a specification, reference being had to the accompanying drawing, forming part thereof.

The characteristic feature of the design resides in the low chair back portion, substantially as shown.

I claim:

The ornamental design for a chair, substantially as shown and described.

HAROLD F. SCRIBNER.
